UNITED STATES PATENT OFFICE.

NEHEMIAH ELLIS, OF WINDFALL, INDIANA.

DESIGN FOR A KRAUT-CUTTER.

SPECIFICATION forming part of Design No. 30,290, dated February 28, 1899.

Application filed February 1, 1899. Serial No. 704,182. Term of patent 7 years.

To all whom it may concern:

Be it known that I, NEHEMIAH ELLIS, a citizen of the United States, residing at Windfall, in the county of Tipton and State of Indiana, have invented and produced a certain new and original Design for Kraut-Cutters; and I do declare the following to be a full, clear, and exact description of the invention, such as will enable others skilled in the art to which it appertains to make and use the same.

The invention has relation to a new and original design for kraut-cutters; and it consists of a kraut-cutter of the configuration shown in the accompanying drawings, in which—

Figure 1 is a perspective view, and Fig. 2 is an edge view, looking in the direction of the cutter.

The leading features of the design consist

in a reversely-curved cutter-blade, the upper edge of which tapers from its central portion to its ends, while its lower edge lies in a true horizontal plane. A handle projects from the upper edge of the cutting-blade and is formed at its upper end with a handhold.

Having thus described the invention, what I claim, and desire to secure by Letters Patent, is—

The design for a kraut-cutter as herein shown and described.

In testimony whereof I have hereunto set my hand in presence of two subscribing witnesses.

NEHEMIAH ELLIS.

Witnesses:

THOMAS M. DAY,
JOHN C. DAY.
